(57) **CLAIM**

The ornamental design for a wind gauge, as shown and described.

DESCRIPTION

FIG. 1 is a top view of the wind gauge.

FIG. 2 is a front view of the wind gauge.

FIG. 3 is a back view of the wind gauge.

FIG. 4 is a bottom view of the wind gauge.

FIG. 5 is a left side view of the wind gauge; and, FIG. 6 is a right side view of the wind gauge.

The arrowhead appearing in the top view (FIG. 1) is a reference direction arrow for the relative wind direction of the measured wind speed.
